DESIGN FOR AN IDENTIFICATION MEDAL

John Ogden, Pawtucket, R. I., assignor to Irons & Russell Company, a corporation of Rhode Island

Application July 27, 1942, Serial No. 107,720

Term of patent 3½ years

To all whom it may concern:

Be it known that I, John Ogden, a citizen of the United States of America, residing in Pawtucket, county of Providence, and State of Rhode Island, have invented a new, original, and ornamental Design for an Identification Medal, of which the following is a specification, reference being had to the accompanying drawing, forming a part thereof:

Fig. 1 is a face view of the identification medal showing my new design;

Fig. 2 is a back view;
Fig. 3 is a side elevation; and
Fig. 4 is a section on line 4—4 of Fig. 1.
The dominant features of this design are shown in full lines.

I claim:

The ornamental design for an identification medal, substantially as shown and described.

JOHN OGDEN.
